(57) **CLAIM**

The ornamental design for an electrode holder for a spray coating device, as shown and described.

DESCRIPTION

FIG. 1 is a top view of an electrode holder for a spray coating device according to a first embodiment;

FIG. 2 is a left side view of the nozzle of FIG. 1;

FIG. 3 is a right side view of the nozzle of FIG. 1;

FIG. 4 is a front view of the nozzle of FIG. 1;

FIG. 5 is a back view of the nozzle of FIG. 1;

FIG. 6 is a perspective view of the nozzle of FIG. 1; and

FIG. 7 is another perspective view of the nozzle of FIG. 1.

FIG. 8 is a top view of an electrode holder for a spray coating device according to a second embodiment;

FIG. 9 is a left side view of the nozzle of FIG. 8;

FIG. 10 is a right side view of the nozzle of FIG. 8;

FIG. 11 is a front view of the nozzle of FIG. 8;

FIG. 12 is a back view of the nozzle of FIG. 8;

FIG. 13 is a perspective view of the nozzle of FIG. 8; and,

FIG. 14 is another perspective view of the nozzle of FIG. 8.
